MINING MACHINE

Morris P. Holmes, Claremont, N. H., assignor to
 Sullivan Machinery Company, a corporation of
 Massachusetts

Application December 19, 1932, Serial No. 647,945

25 Claims. (Cl. 262—30)

This invention relates to mining machines, and more particularly to improvements in the feeding mechanism of a coal mining machine of the flexibly fed, continuous cutter, bottom cutting type.

An object of this invention is to provide an improved coal mining machine. Another object is to provide an improved mining machine feeding mechanism. A further object is to provide an improved feeding mechanism for a coal mining machine of the flexibly fed, continuous cutter, bottom cutting type. Another object is to provide an improved coal mining machine of the combined room and pillar and longwall type having improved feeding mechanism for propelling the machine during cutting in accordance with either the room and pillar or longwall systems of mining. A further object is to provide, in a machine of the above character, an improved feeding mechanism wherein relatively rotatable feeding members each adapted to cooperate with flexible feeding means are employed for feeding the machine laterally across the coal face during cutting in accordance with the room and pillar system, and for feeding the machine in an endwise direction along the coal face during cutting in accordance with the longwall system, the machine being provided with a pivoted kerf cutter disposable in a position lengthwise of the machine during room and pillar cutting or in right angle positions at either side of the machine during longwall cutting. Still another object is to provide, in a machine of the above character, an improved feeding mechanism wherein flexible-element-engaging, feed operating, and controlling members are employed for feeding and guiding the machine during cutting in accordance with the room and pillar system, the feed controlling member acting as a safety member during cutting in accordance with the longwall system, particularly while cutting on pitching coal seams wherein there is inherent danger of breakage or release of the feed member during the cutting operation as the machine moves up the steeply inclined seam; the control member at that time acting to prevent movement of the machine down the pitch in the event of breakage or release of the feed operating member. A still further object is to provide improved driving means for the feed operating and controlling members of such a machine. These and other objects and advantages of the invention will, however, hereinafter more fully appear.

In the accompanying drawings there is shown for purposes of illustration one form which the invention may assume in practice.

In these drawings,—

Fig. 1 is a plan view of the illustrative embodiment of the improved coal mining machine.

Fig. 2 is a side elevational view of the mining machine shown in Fig. 1.

Fig. 3 is an enlarged horizontal sectional view, with parts shown in plan, taken substantially on the line 3—3 of Fig. 2.

Fig. 4 is an enlarged transverse vertical sectional view taken substantially on the line 4—4 of Fig. 3.

Fig. 5 is an enlarged longitudinally extending vertical sectional view taken substantially on the line 5—5 of Fig. 3.

Fig. 6 is a fragmentary view, partially in elevation and partially in section, showing portions of the transmission mechanism shown in Fig. 3.

Fig. 7 is a transverse vertical section substantially on the line 7—7 of Fig. 6.

Fig. 8 is a transverse vertical section taken substantially on the line 8—8 of Fig. 6.

Fig. 9 is a detail sectional view taken substantially on the line 9—9 of Fig. 4.

In this illustrative construction, the improved feeding mechanism is shown embodied in a coal mining machine of the combined room and pillar and longwall type, although it will be evident that the improved feeding mechanism may be employed in other types of mechanisms. The mining machine disclosed herein comprises a flat, rectangular-shaped machine frame 1 having a plane bottom surface 2 adapted to rest upon and slide in any direction over the mine floor. The machine frame 1, in this instance, comprises a central motor section 3, a cutter carrying section 4 and a feed frame section 5, the motor section being arranged between the cutter and feed frame sections, and these sections when united forming an extremely low compact machine frame.

Pivoted at 6 on the cutter frame section 4 for horizontal swinging movement relative thereto into positions lengthwise of the machine, as shown in full lines in Fig. 1, or in right angle positions at either side of the machine, as indicated in dotted lines in Fig. 1, is an elongated plane cutter bar 7 carrying on its margin for circulation thereabout an endless cutter bit carrying cutter chain 8. Mounted on the cutter bar is a usual locking element 9 for locking the cutter bar in its different positions about its pivot relative to the frame. Housed within the motor section 3 is a horizontal motor, and this motor construction and the construction of the cutter frame section and the particular driving connections between the motor and

30

the cutter chain are identical to those described in my Patent No. 1,815,872, granted July 21, 1931, and therefore a more detailed description thereof is herein considered unnecessary. Driven 5 by the end of the motor opposite from the cutter chain drive and carried by the feed frame section 5 at the end of the machine remote from the cutter bar is the improved feeding mechanism generally designated 10.

Now referring to the improved feeding mechanism, it will be noted that arranged within a chamber 11 extending transversely through the lower portion of the feed frame is a feed operating member, herein a feed drum 12 of relatively large diameter and disposed on a vertical axis lying midway between the sides of the machine frame in the central longitudinal vertical plane of the machine as shown in Fig. 1. Disposed at the top of the feed frame in superimposed coaxial relation with the feed drum 12 is a controlling member, herein a controlling or safety retarding drum 13. The bottom surface of the feed drum 12 lies in planes adjacent the bottom plane surface of the machine frame, while the bottom surface of the upper drum 13 lies in planes adjacent the top plane surface of the machine frame. Wound upon the feed drum 12 is a feed cable 14, while wound upon the drum 13 is a feed controlling or safety retarding cable 15. Arranged in transverse planes adjacent the feed drum on parallel vertical axes and in pairs at opposite sides of the feed frame are guide sheaves 16, 16, while arranged in coaxial relation therewith in transverse planes adjacent the upper drum 13 are similar guide sheaves 17, 17, these guide sheaves being adapted to guide the feeding and controlling cables, thereby enabling the cables to be extended in various directions relative to their respective drums. Detachably secured to the cutter frame section 4 is a hanger mounting 18 carrying a swing arm 19, on the lower end of which is journaled a guide sheave 20 around which the feeding cable 14 is adapted to be extended during lateral feeding of the machine in accordance with the room and pillar system. The cable 14 is connectible in a well known manner to the locking element 9 to effect swinging of the cutter bar 7 about its pivot. During cutting from left to right in accordance with the room and pillar system, that is in a direction opposite from that shown in full lines in Fig. 1, the swing arm hanger 18 is detached from the left hand side of the cutter frame and is transposed to the opposite side of the frame, and the feeding and controlling cables are extended from the machine in an opposite manner. As the various arrangements of the feeding and controlling cables relative to their respective drums and guide sheaves to effect feed of the machine in accordance with either the room and pillar or longwall systems of mining are well known to those skilled in the art, and as the feed cables may be extended from their respective drums in any preferred direction, further description of the particular arrangements of the cables and the mode of operation of the machine is not deemed necessary.

Now referring to the specific driving connections between the motor and the feed operating and controlling drums 12 and 13, it will be noted that fixed to the motor power shaft 25, as shown in Fig. 3, is a spur motor pinion 26 meshing with a spur gear 27 keyed to a horizontal longitudinally extending shaft 28, herein arranged parallel with the motor power shaft and suitably

journaled within the feed frame 5. Formed on this shaft at the end thereof opposite from the gear 27 is a spur pinion 29 meshing with a spur gear 30 keyed to a horizontal longitudinally extending shaft 31, herein arranged parallel with the shafts 25, 28 and likewise suitably journaled within the feed frame. Secured to and driven by the shaft 31 and arranged at the end thereof opposite from the spur gear 30 is a spur pinion 32 meshing with a spur gear 33 keyed to a horizontal longitudinally extending shaft 34, herein arranged parallel with the shaft 31 and preferably in axial alinement with the shaft 28 and likewise suitably journaled within the feed frame. Secured to the end of the shaft 34 opposite from the gear 33 is a spur pinion 35 meshing with a spur gear 36 arranged coaxially with the spur gear 30 and surrounding and journaled on the shaft 31. Suitably journaled within bearings carried within the gears 30 and 36 and arranged coaxially with and surrounding the transmission shaft 31 is a tubular shaft 37 having formed thereon, intermediate its ends, a worm 38. The gear train including gears 26, 27, 29 and 30 constitutes a high speed drive, while these gears and, additionally, the reduction gears 32, 33, 35 and 36 constitute a slow speed drive; and these drives are selectively connectible with the opposite ends of the worm shaft 37 through friction disc clutches 39 and 40, respectively.

The particular clutch mechanism and the actuating and controlling means for the clutch mechanism are similar in design to those described in my copending application, Ser. No. 555,328, filed August 5, 1931, now matured into Patent No. 1,968,769, patented July 31, 1934. The clutch actuating and controlling mechanism will now be described. Fast speed rotation of the worm shaft 37 is effected herein by direct connection of the shaft with the high speed gear 30; while continuous rotation of the shaft at a slow speed and intermittent rotation at a number of different still slower mean speeds are effected herein by the following mechanism. A ball-bearing clutch-applying element 41 reciprocably mounted on the shaft 37 is operative to transmit the pressure of a clutch shipper element 42, which is pivotally supported at 43 on the feed frame, to effect loading of the friction clutch 39 and thereby to effect connection between the high speed gear 30 and the shaft 37. A similar clutch-applying member 44 is arranged adjacent the opposite end of the shaft 37 and is movable by a clutch shipper 45 to effect loading of the friction clutch 40 and thereby to effect connection of the low speed gear 36 to the shaft 37. The shipper 45 is pivotally supported at 46 on the feed frame. Formed integral with the low speed gear 36 at one side thereof is a cam surface 47 with which engages a pin 48, and this pin is slidably guided for linear movement in a bore formed in the bearing bracket 49 which supports the bearings for the shafts 31 and 34, as shown in Figs. 3 and 6. At its opposite end this pin 48 is pivotally connected at 50 with one end of a lever 51, whose opposite end 52 is pivotally connected to a threaded member 53 which receives the outer end of a threaded rod 54. The opposite inner end of the rod 54 is provided with an enlargement 55 forming a shoulder 56, and a spring 57 is compressed between a nut 58 cooperating with the threaded outer end of the rod 54 and a collar 59 slidably mounted upon the rod 54 adjacent the inner end of the latter and normally engaging the shoulder 56. The enlarged inner end 55 of

the rod 54 passes through a trunnion device 61 supported by the shipper member 45 which carries, at its opposite sides from its pivot 46, clutch-applying elements 62. It will be evident from the foregoing description that movement to the left of the rod 54 in Figs. 3 and 6 will result in a transmission of no pressure to the clutch shipper member 45 until the sliding collar 59 engages the end of the trunnion device 61; but that further movement to the left, in these figures, of the rod 54 will thereafter impart a load to the shipper member 45 which will be determined by the extent of the movement of the rod and the degree of compression of the spring 57. The pin 48 may be held against sliding movement within its guide when desired by means of any suitable device, such as a set screw 63 threadedly supported in the top of the bearing bracket 49 as described in the above mentioned application and as shown in Fig. 7. A movable fulcrum for the lever 51 is provided by trunnion devices 64 which are held upon a longitudinally movable rod 65 between a collar 66 on the latter and the inner end of a sleeve 67. A key 68 extends through the sleeve and into the rod.

The inner end of the longitudinally movable rod 65 carries a nut 69 which, on movement of the rod to the right as viewed in Figs. 3 and 6, applies pressure to trunnion devices 70 surrounding the rod 65 and pivotally mounted in the outer end of the shipper member 42. The rod 65 extends through the sleeve 67, as indicated above, and sleeve 67 is slidable within but splined by means of the key 68 to one hub 71 of a lever 72, the opposite hub of this lever being threadedly connected at 73 within the end wall of the feed frame. Threadedly connected to the outer hub of this lever at 74 is a rotatable operating handle 75. The rod 65 is provided with an enlarged head 76 engageable with the outer end surface of this handle. Obviously, collar 66 and head 76 hold the trunnion device 64, sleeve 67 and the wall of the handle 75 in fixed relation, as regards relative longitudinal movement between them. The handle 75 is in the form of a nut, and movement of the shaft 65, trunnion devices 64, and sleeve 67 longitudinally is effected by rotation of the handle 75 relative to the hub of the lever 72. Rotation of the handle 75 in a direction to cause movement of the rod 65 toward the right in Figs. 3 and 6 results in loading of the friction clutch 39 and driving of the worm shaft 37 directly by the high speed gear 30. Rotation of the handle 75 in a direction to effect movement of the rod 65 toward the left in Figs. 3 and 6 moves the fulcrum 64 of the lever 51 toward the left, and thereby moves the pin 48 into engagement with the cam surface 47; and upon movement of the fulcrum sufficiently far to the left, the other end of the lever 51 will have sufficient throw so that the shoulder 56 will pass inside the trunnion devices 61 and permit the collar 59 to contact with the trunnion devices and the spring 57 to load the friction clutch 40. Obviously, when the spring 57 is under sufficient compression so that it will yield only when a pressure adequate to effect power transmission through the discs of the friction clutch 40 is applied to the collar 46, the adjustment of the fulcrum device 66 may effect rotation of the shaft 57 at a low speed by the low speed gear 36 for any desired part of each revolution of the latter. When the rod 65 is moved to the left so far that the collar 59 continuously presses under the pressure of the spring against the fulcrum device 61,

continuous rotation of the worm shaft 37 will take place, and the spring 57 will compress during each rotation of the low speed gear 36 an amount substantially equal to the full throw of the cam 47; but since the load of the spring is desirably above the minimum necessary to effect power transmission through the friction clutch discs, there will be no release even when the lowest point in the cam 47 is opposite the pin 48. However, by moving the rod 65 graduated amounts toward the right in Fig. 3, the period of drive during each rotation of the gear 36 may be progressively reduced until it is entirely discontinued. It will be understood that the splined connection between member 71 and the sleeve 67 and rod 65 permits longitudinal movement of the last two elements relative to, and through, the member 71; but rotation of member 71 will always be effective to rock the shaft or rod 65, while the threaded connection at 73 has such a fine lead that material longitudinal variation in the position of the rod 65 will not be caused by the necessary rotation of 71.

Obviously, if the pin 48 is locked by the set screw 63 in position within its guide where it is not engaged by the cam 47 at all, there will be no variation in the speed transmitted, but there will be a definitely limited pressure applied to the friction clutch 40, and a predetermined slow speed drive adapted to slip on overloading will be available.

Now referring to the improved driving connections between the tubular worm shaft 37 and the feed operating and controlling drums 12 and 13, it will be observed that the worm 38 meshes with a worm wheel 80 disposed on a vertical axis parallel with the drum axis and likewise lying midway between the sides of the feed frame in the longitudinal vertical plane of the machine. This worm wheel is connectible by interlocking clutch mechanisms 81 and 82, respectively, (see Fig. 9) to aligned shafts 83 and 84, the shafts arranged coaxially with the worm wheel 80 and suitably journaled within the feed frame. The lower shaft 84 carries a spur pinion 85 meshing with a large internal gear 86 formed on the lower feed drum 12, while the upper shaft 83 has formed thereon a similar pinion 87 meshing with a large internal gear 88 formed integral with the upper controlling, or safety, drum 13. The shafts 83, 84 are separately or simultaneously connectible in driving relation with the worm wheel 80 by the interlocking clutch mechanisms 81, 82, and these clutch mechanisms each comprise interlocking clutch plungers 89 slidably guided within radial bores 90 formed in the hub of the worm wheel 80, and are normally held in released position by coiled springs 91. Each mechanism is provided with a clutch shipper 92 having formed internally thereon a cam surface 93 engageable with corresponding surfaces 94 formed on the clutch plungers 89, so that when the clutch members 92 are shoved inwardly toward one another, the cam surfaces force the clutch plungers into interlocking engagement with grooves 95 formed in the shafts 83, 84. These shipper members are provided with shipper levers 96 and 97, respectively, pivotally mounted at 98 on a horizontal axis within the feed frame. The mechanism for swinging the shipper levers 96, 97 about their respective pivots comprises a cam member 99 splined to the rod 65 and having cam slots 100 (see Fig. 4) engageable with pin-like projections 101 carried on the operating arms of the levers 75.

It will thus be seen that when the lever 72 is rotated, the sleeve 67 and the rod 65 splined thereto are rotated therewith, thereby rotating the cam 99, and as a result, swinging the shipper levers 96, 97 about their pivots. When the cam 99 is in one position, that is, when the projections 101 ride on the cam-like surfaces 102 of the slots, both the shipper levers 96, 97 are held inwardly to connect, through the interlocking clutch mechanisms, the shafts 83, 84 to the worm wheel 80. In another position of the cam member 99, the projections 101 lie at the bottoms of the cam surfaces, and at that time the levers 94, 95 are swung outwardly with both of the interlocking clutch mechanisms released. When the cam member 99 is in still another position, the levers are held in their released position with the clutch mechanisms both disconnected. By moving the cam 99 into still other positions, one or the other 20 of the clutch mechanisms 81, 82 may be connected while the other is released. It will thus be seen that, depending upon the position of the cam 99, the drums 12 and 13 may be separately or simultaneously driven.

Under certain conditions it is desirable to brake rotation of the controlling or retarding drum 13, for instance when the drum is disconnected from its drive and the machine is operating in accordance with the longwall system on a steeply inclined coal seam, it at that time being desirable for the controlling drum to act as a retarding or braking drum to control the downward movement of the machine along the incline or to hold the machine against movement down the incline 30 in the event of breakage or release of the feeding member. This braking means comprises an adjusting screw 105 (see Fig. 5) threadedly connected within a boss 106 integral with the feed frame and forming a bearing support for the upper drum. This screw is provided with a cylindrical head 107 having a transverse opening 108 within which there is slidably mounted an operating handle 109. The lower surface of the head 107 engages a cylindrical braking plate 110 supported on the boss 106 and held against rotation relative to the latter by a transverse tongue and groove connection 111, and engageable with a braking ring 112 to force the latter into frictional braking engagement with the upper surface of the 40 drum 13. The lower drum 12 is journaled within the feed frame in the manner similar to that described in the application mentioned above.

As a result of this invention it will be noted that an improved coal mining machine of the combined room and pillar and longwall type is provided having improved feeding mechanism whereby the machine may operate in accordance with either the room and pillar or longwall systems of mining. It will further be evident that there is provided an improved longwall coal mining machine of the pivoted bar type having a plurality of feed operating and controlling members arranged in an improved manner on the machine and having improved driving and controlling 55 means therefor. It will further be noted that an improved mining machine feeding mechanism is provided wherein the feed operating and controlling members may be driven at a predetermined high speed, at a predetermined slow speed, or at any desired speed from its maximum slow speed down to zero, as desired. These and other uses and advantages of the improved mining machine will be clearly apparent to those skilled in the art.

While there is in this application specifically described one form which the invention may as-

sume in practice, it will be understood that this form of the same is shown for purposes of illustration and that the invention may be modified and embodied in various other forms without departing from its spirit or the scope of the appended claims. 5

What I claim as new and desire to secure by Letters Patent is:

1. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means and arranged in superimposed relation on vertical axes, one in horizontal planes above the top of the machine frame and the other in horizontal planes adjacent the bottom thereof. 10

2. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means and arranged in superimposed coaxial relation on a vertical axis, one in horizontal planes above the top of the machine frame and the other in horizontal planes adjacent the bottom thereof. 20

3. In a mining machine, a machine frame adapted to rest upon and slide in any direction over the mine floor, a kerf cutter projecting from said frame, and motor operated devices for feeding and guiding the machine including relatively rotatable feed operating and controlling members respectively adapted to cooperate directly with flexible feeding and controlling means, and driving means for rotating said members continuously at a fast speed and intermittently at a slow 30 speed including aligned relatively rotatable shafts arranged with their axes lying in a vertical plane extending longitudinally of the machine, a driving gear therefor coaxial therewith, continuous fast and intermittent slow speed driving means 40 selectively connectable in driving relation with said driving gear, operative driving connections between said shafts and said members respectively, and selectively operable clutch mechanisms for connecting said shafts in driving relation with 50 said driving gear.

4. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means, driving means for rotating said members including aligned relatively rotatable shafts 60 arranged with their axes lying in a vertical plane extending longitudinally of the machine, a driving gear therefor coaxial therewith, continuous fast and intermittent slow speed driving means selectively connectable in driving relation 65 with said gear, operative driving connections between said shafts and said members respectively, selectively operable clutch mechanisms for connecting said shafts in driving relation with said gear, and operating means for said clutch mechanisms for separately or simultaneously connecting the same. 70

5. In a mining machine, a machine frame adapted to rest upon and slide in any direction over the mine floor, a kerf cutter projecting from 75

5 said frame, and motor operated devices for feeding the machine including relatively rotatable feed operating and controlling members each adapted to cooperate directly with flexible feeding means and arranged in superimposed relation, driving means for rotating said members at a continuous predetermined high speed and intermittent slow variable speeds, shafts one individual to each member, means for selectively connecting said shafts in driving relation with said driving means, and braking means for one of said members.

10 6. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means and arranged in superimposed relation, means for independently rotating said members selectively at different predetermined speeds and at variable lower speeds including driving means rotatable to effect drive at such speeds, driving shafts one individual to each member, and means for selectively connecting said shafts for drive by said driving means, and braking means for the upper member.

15 7. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means and arranged in superimposed relation, the controlling member arranged in horizontal planes above the top of the machine frame and the feed operating member in horizontal planes adjacent the bottom thereof.

20 8. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means and arranged in superimposed coaxial relation on a vertical axis, the controlling member arranged in horizontal planes above the top of the machine frame and the feed operating member in horizontal planes adjacent the bottom thereof.

25 9. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means and arranged in superimposed relation, the controlling member arranged in horizontal planes above the top of the machine frame and the feed operating member in horizontal planes adjacent the bottom thereof, driving means for said members, and means for braking said controlling member when the latter is disconnected from its drive.

30 10. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feed-

35 ing means and arranged in superimposed coaxial relation on a vertical axis, the controlling member arranged in horizontal planes above the top of the machine frame and the feed operating member in horizontal planes adjacent the bottom thereof, driving means for said members, and means for braking said controlling member when the latter is disconnected from its drive. 5

40 11. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means and arranged in superimposed relation on vertical axes, one in horizontal planes above the top of the machine frame and the other in horizontal planes adjacent the bottom thereof, and driving means for rotating said members including fast and slow speed drives, said slow speed drive including selective continuous or intermittent driving connections. 10

45 12. In a mining machine, a machine frame adapted to rest upon and slide in any direction over the mine floor, a kerf cutter projecting from said frame, and motor operated devices for feeding and guiding the machine including relatively rotatable feed operating and controlling members respectively adapted to cooperate directly with flexible feeding and controlling means and arranged in superimposed relation on vertical axes, one in horizontal planes above the top of the machine frame and the other in horizontal planes adjacent the bottom thereof, and driving means for rotating said members including fast and slow speed drives, said slow speed drive including selective continuous or variable intermittent driving connections through which both members are driven for rotating said members 50 continuously at a maximum low speed and intermittently through a wide range of low speeds between zero and said maximum low speed. 35

55 13. In a mining machine, a machine frame adapted to rest upon and slide in any direction over the mine floor, a kerf cutter projecting from said frame, and motor operated devices for feeding and guiding the machine including relatively rotatable feed operating and controlling members respectively adapted to cooperate directly with flexible feeding and controlling means and arranged in superimposed relation on vertical axes, one in horizontal planes above the top of the machine frame and the other in horizontal planes adjacent the bottom thereof, and driving means for rotating said members continuously at a maximum low speed and intermittently at a low speed slower than said low speed including a friction clutch through which both members are driven, loading means for said clutch including a yielding connection and means for intermittently or continuously tensioning said yielding connection. 60 50

65 14. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means, and driving means for rotating said members including aligned relatively rotatable shafts arranged with their axes lying in a vertical plane extending longitudinally of the machine frame, a driving gear therefor coaxial therewith, 70 75

- plural speed driving means for said gear, operative driving connections between said shafts and said members respectively, and selectively operable clutch mechanisms for connecting said shafts 5 in driving relation with said gear.
15. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means, driving means for rotating said members including aligned relatively rotatable shafts 10 arranged with their axes lying in a vertical plane extending longitudinally of the machine frame, a driving gear therefor coaxial therewith, plural speed driving means for said gear, operative driving connections between said shafts and said 15 members respectively, selectively operable clutch mechanisms for connecting said shafts in driving relation with said gear, and operating means for said clutch mechanisms for separately or simultaneously connecting the same. 20
25. 16. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means, and driving means for rotating said members including aligned relatively rotatable shafts disposed on vertical axes, a driving gear 30 therefor coaxial therewith, operative driving connections between said shafts and said members respectively, and selectively operable clutch mechanisms for connecting said shafts in driving relation with said gear. 35
35. 17. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means, driving means for rotating said members including aligned relatively rotatable shafts disposed on vertical axes, a driving gear therefor 40 coaxial therewith, operative driving connections between said shafts and said members respectively, selectively operable clutch mechanisms for connecting said shafts in driving relation with said gear, and operating means for said clutch mechanisms for separately or simultaneously connecting the same. 45
50. 18. In a mining machine, a machine frame adapted to rest upon and slide in any direction over the mine floor, a kerf cutter projecting from said frame, and motor operated devices for feeding the machine including relatively rotatable feeding and controlling drums disposed on vertical axes, a driving gear arranged between said drums and disposed on a vertical axis, aligned relatively rotatable shafts coaxial with said driving gear, operator-controllable interlocking clutch mechanisms for selectively connecting said shafts to said gear, and driving connections between said shafts and said drums, respectively. 55
55. 19. In a mining machine, a machine frame adapted to rest upon and slide in any direction over the mine floor, a kerf cutter projecting from said frame, and motor operated devices for feeding the machine including relatively rotatable feed operating and controlling members each 60
- adapted to cooperate directly with flexible feeding means and arranged in superimposed relation on vertical axes, one in horizontal planes adjacent the top of the machine frame and the other in horizontal planes adjacent the bottom thereof, and motor operated driving means for rotating said members at a low speed including a low speed drive, said low speed drive including a selective continuous or intermittent low speed driving connection. 5
65. 20. In a mining machine, a machine frame adapted to rest upon and slide in any direction over the mine floor, a kerf cutter projecting from said frame, and motor operated devices for feeding the machine including relatively rotatable feed operating and controlling members each adapted to cooperate directly with flexible feeding means and arranged in superimposed relation on vertical axes, one in horizontal planes adjacent the top of the machine frame and the other in horizontal planes adjacent the bottom thereof, and motor operated driving means for rotating said members at a low speed including a friction clutch, and means for automatically intermittently loading said friction clutch at predetermined timed intervals. 10
70. 21. In a mining machine, a machine frame adapted to rest upon and slide in any direction over the mine floor, a kerf cutter projecting from said frame, and motor operated means for feeding and guiding the machine including relatively rotatable feed operating and controlling members respectively adapted to cooperate directly with flexible feeding and controlling means and arranged in superimposed relation on said frame, means for independently rotating said members selectively at different predetermined speeds and at variable lower speeds, shafts one individual to each member, and means for selectively connecting said shafts in driving relation with said 15
75. 22. In a mining machine, a machine frame adapted to rest upon and slide in any direction over the mine floor, a kerf cutter projecting from said frame, and motor operated means for feeding and guiding the machine including relatively rotatable feed operating and controlling members respectively adapted to cooperate directly with flexible feeding and controlling means and arranged in superimposed spaced-apart relation on said frame, means for independently rotating said members selectively at different predetermined speeds and at variable lower speeds including a driving element arranged in the space between said members, shafts one individual to each member, and means for selectively connecting said shafts in driving relation with said 20
80. 23. In a mining machine, a machine frame adapted to rest upon and slide in any direction over the mine floor, a kerf cutter projecting from said frame, and motor operated means for feeding and guiding the machine including relatively rotatable feed operating and controlling members respectively adapted to cooperate directly with flexible feeding means and arranged in superimposed, spaced-apart, coaxial relation, one in horizontal planes near the top of the machine frame and the other in horizontal planes near the bottom of said frame, and a plural predetermined speed transmission mechanism arranged in the space between said superimposed members for driving said members, either separately or simultaneously, at predetermined high 25 and low speeds. 75

24. In a mining machine, a machine frame adapted to rest upon and slide in any direction over the mine floor, a kerf cutter projecting from said frame, and motor operated means for feeding and guiding the machine including relatively rotatable feed operating and controlling members respectively adapted to cooperate directly with flexible feeding means and arranged in superimposed, spaced-apart, coaxial relation, 5 one in horizontal planes near the top of the machine frame and the other in horizontal planes near the bottom of said frame, a plural predetermined speed transmission mechanism arranged in the space between said superimposed 10 members for driving said members, either separately or simultaneously, at predetermined high and low speeds, and a braking means for one of said members for retarding rotation of said member when disconnected from said transmission mechanism. 15
25. In a mining machine, a machine frame adapted to rest upon and slide in any direction over the mine floor, a kerf cutter projecting from said frame, and motor operated means for feeding and guiding the machine including relatively rotatable feed operating and controlling members respectively adapted to cooperate directly with flexible feeding means and arranged in superimposed, spaced-apart, coaxial relation, 5 one in horizontal planes near the top of the machine frame and the other in horizontal planes near the bottom of said frame, a plural predetermined speed transmission mechanism arranged in the space between said superimposed members, said slow speed drive including selective continuous 10 or intermittent driving connections through which both members are driven for rotating said members continuously at a maximum low speed and intermittently at low speeds slower than said maximum low speed. 20

MORRIS P. HOLMES.
